U.S. CL. D34—5

FIG. 5.FIG. 6.

FIG. 1 is a front elevation of an exerciser embodying our new design;

FIG. 2 is a side elevation thereof taken from the right of FIG. 1, with the parts separated, the opposite side being a mirror image thereof;

FIG. 3 is a top plan view thereof;

FIG. 4 is a rear view thereof;

FIG. 5 is a front elevation of an exerciser embodying our new design and comprising another embodiment of our invention; and

FIG. 6 is a side elevation thereof taken from the right of FIG. 5, with the parts separated.

The top and the rear of FIG. 5, not shown, correspond to FIGS. 3 and 4, except for the differences apparent between FIGS. 5 and 1.

We claim:

The ornamental design for an exerciser, as shown and described.
